[57] CLAIM

The ornamental design for a center of gravity level, substantially as shown and described.

DESCRIPTION

FIG. 1 is a front elevational view of a center of gravity lever showing our new design;

FIG. 2 is a top plan view thereof;

FIG. 3 is a bottom plan view thereof;

FIG. 4 is a rear elevational view thereof;

FIG. 5 is a left side elevational view thereof;

FIG. 6 is a right side elevational view thereof.
